STUD SCREW WRENCH

Fred C. Wegner, United States Navy

Application October 16, 1934, Serial No. 748,500

6 Claims. (Cl. 81—53)

(Granted under the act of March 3, 1883, as
amended April 30, 1928; 370 O. G. 757)

This invention relates to a stud screw wrench and has for an object to provide an improved tool for driving and extracting stud screws.

Stud screws, as is well known, are threaded male elements having no definite head for receiving an operating tool. They are used in many places. For example, in securing the cylinder head to an engine block, a plurality of stud screws are inserted in the engine block and intended to project through suitably provided apertures in the cylinder head and then securing nuts are placed on the ends of the stud screws on the outside of the cylinder head. In this use, as in many other uses, it is often necessary to remove and replace one or more stud screws from the engine block. Previously this was generally done by the use of a Stillson or pipe wrench placed about the stud screw, generally below the outer threads thereof. This method is not applicable should the threads extend the entire length of the stud screw as it tends to mar the threads. Even when there is an unthreaded portion on the stud screw, however, this previous method is undesirable because the body of the male member is generally scratched and marred and will not fit easily and smoothly through the aperture provided in the cylinder head.

With this invention it is possible to drive or to remove the stud screw from the engine block without marring either the body or the threads of the stud screw. It is possible to easily and quickly place this tool into operative position and then, once it is in operative position, to secure a positive grip on the stud screw for either securing the screw firmly in the engine block or for removing the stud screw from the engine block, no matter how firmly it is already secured therein.

Other objects, novel features, and advantages of this invention will be apparent from the following specification and drawing, wherein:

Fig. 1 is a top plan view of the assembled tool;

Fig. 2 is a bottom plan view;

Fig. 3 is a top plan view of the body;

Fig. 4 is a sectional view on line 4—4, Fig. 1;

Fig. 5 is a bottom plan view of the sleeve; and

Fig. 6 is an elevational view of the locking spring.

There is shown at 10 the assembled stud tool or wrench which includes a body 11, sleeve 12, and locking spring 13. Body 11, as shown, is hexagonal in outline so as to allow an ordinary nut wrench to be applied thereto for operating the tool although it will be understood that instead, if desired, a handle may be integrally attached to the body 11. The body 11 is provided

with an internal aperture extending therethrough, this aperture being divided into a plurality of cammed surfaces 14. Four of these cammed surfaces 14 are shown but more or less may be employed, as desired. The sleeve 12 is internally threaded as at 15, these threads 15 being adapted to cooperate with the male threads of the stud screw. The sleeve is divided by a plurality of longitudinal slots 16 extending as far as adjoining flange 17. The slots 16 divide the sleeve into a plurality of sections 18, the external surfaces of which are cammed as at 19, the cam 19 being of a size and shape to cooperate with the internal cam 14 in the body 11. The flange 17 is provided with a locking pin groove 20 adapted to cooperate with the locking pin 21 extending from the surface of the body 11.

To assemble the tool the sleeve 12 is inserted through the aperture in the body 11, the cammed surfaces 19 of the sleeve coming within the cammed surfaces 14 in the body 11. After the sleeve 12 has been inserted in the body 11, the locking spring 13 is placed in an appropriately formed slot 22 in the other end of the sleeve sections 18 so as to hold the sleeve from falling out of the body 11. It will be observed, however, that when in operative position the spring 22 and flange 17 allow the sleeve 13 and body 11 to have relative longitudinal movement to each other a distance at least equal to the length of the locking pin 21 so that the pin may be placed within the groove 20 or may be removed therefrom while the sleeve and body are held in assembled position.

To operate this invention the body and sleeve 35 are moved longitudinally relative to each other so as to bring the pin 21 within its groove 20, thereby preventing relative rotation between the sleeve and the body. While being held in this position any ordinary wrench is applied to the outside of 40 the body 10 and it may be threaded on to the stud screw in the same manner as any ordinary nut, the pin 21 and groove 20 causing the sleeve 12 to partake of the rotation of the body 11. When the tool has been threaded onto the stud screw a 45 sufficient distance, the body 11 is then displaced longitudinally to allow the locking pin 21 to be displaced from its groove 20. Then, as for driving the stud into the engine block, the rotation of the body 11 is continued by means of the 50 operating tool. The body 11 commences to rotate relative to the sleeve 12 bringing the cammed surfaces 14 of the body 11 against the cammed surfaces 19 of the sleeve portions 18, tending to squeeze the sleeve portions toward each other 55

tightly on the stud screw until ultimately the sleeve portions are locked firmly against the threads of the stud screw and the sleeve and stud screw partake of the rotation of the body 11.

5 To remove the tool, the body 11 is merely reversed in its rotation releasing the cammed surfaces from pressure against each other and allowing the tool to be removed from the screw. To remove the stud screw from the engine block, the 10 assembly is placed on the screw in a reversed position so that when the pin 21 is removed from its groove 20 the cammed surfaces 14 and 19 will operate in a reverse direction and cause the sleeve to be tightened about the stud screw in an 15 extracting instead of a driving direction.

The invention described herein may be manufactured and used by or for the Government of the United States of America for governmental purposes without the payment of any royalties 20 thereon or therefor.

I claim:

1. A stud extracting and driving tool comprising an internally apertured body member, a longitudinally slotted internally threaded cylinder sleeve member adapted to extend through said internally aperture body member, and cooperating external eccentric cammed surfaces on said sleeve member and internal eccentric cammed surfaces on said body member, said surfaces being parallel to the axis of said cylindrical sleeve.

2. A stud extracting and driving tool comprising an internally apertured body member, a longitudinally slotted internally threaded sleeve member adapted to extend through said internally aperture body member, cooperating external eccentric cammed surfaces on said sleeve member and internal eccentric cammed surfaces on said body member, and means for locking said 35 sleeve member and body member against relative rotation preventing cooperation of said cammed surfaces permitting said sleeve and body members to be moved as a unit.

3. A stud extracting and driving tool comprising an internally apertured body member, a longitudinally slotted internally threaded sleeve member adapted to extend through said internally apertured body member, cooperating external cammed surfaces on said sleeve member 45 and internal cammed surfaces on said body member, and means for locking said sleeve member and body member against relative rotation preventing cooperation of said cammed surfaces, said

means comprising a pin on one of said members and a cooperating groove on the other of said members, said pin and groove being adapted to be displaced from operative position by slight relative longitudinal displacement of said body 5 and sleeve.

4. A stud extracting and driving tool comprising an internally apertured body member, a longitudinally slotted internally threaded sleeve member adapted to extend through said internally apertured body member, cooperating external eccentric cammed surfaces on said sleeve member and internal eccentric cammed surfaces on said body member, means for locking said sleeve member and body member against relative 10 rotation preventing cooperation of said cammed surfaces while permitting said members to be rotated as a unit, and means preventing longitudinal separation of said sleeve and said body.

5. A stud extracting and driving tool comprising an internally apertured body member, a longitudinally slotted internally threaded sleeve member adapted to extend through said internally apertured body member, cooperating external eccentric cammed surfaces on said sleeve member and internal eccentric cammed surfaces on said body member, means for locking said sleeve member and body member against relative rotation 20 preventing cooperation of said cammed surfaces while permitting said members to be rotated as a unit, and means preventing longitudinal separation of said sleeve and said body, said latter means comprising an externally projecting flange at one end of said sleeve and a locking spring at the other end of said sleeve.

6. A stud extracting and driving tool comprising an internally apertured body member, a longitudinally slotted internally threaded sleeve member adapted to extend through said internally apertured body member, cooperating external eccentric cammed surfaces on said sleeve member and internal eccentric cammed surfaces on said body member, means for locking said sleeve member and body member against relative rotation 25 permitting said members to be rotated as a unit, and means preventing longitudinal separation of said sleeve and said body, said latter means comprising an externally projecting flange at one end of said sleeve and a locking spring at the other end of said sleeve, said flange 30 integrally uniting the cammed threaded portions of said sleeve.
